HIGH POTENTIAL TRANSMISSION INSTALLATION

Application filed August 23, 1928. Serial No. 301,538.

This invention relates to electric transmission lines and has for one object the provision of a transmission system that shall be of improved construction and operation. 5
Another object is to provide a ground wire construction for transmission lines that will tend to increase the capacity of the line to ground and at the same time, assist in dissipating the energy of charges induced by abnormal disturbances. Other objects will appear from the following description.

The invention is exemplified by the combination and arrangement of parts shown in the accompanying drawings and described in the following specification and it is more particularly pointed out in the appended claims. This application is in part a continuation of application Serial Number 290,343, filed July 5, 1928.

20 In the drawings:

Fig. 1 is an elevation of a ground wire support comprised in the present invention.

Fig. 2 is a view at right angles to Fig. 1.

25 Fig. 3 is a diagrammatic view of a portion of a transmission line having the present invention applied thereto.

Fig. 4 is a modified form of arcing gap.

Fig. 5 is a section on line 5—5 of Fig. 4.

30 Figs. 6, 7 and 8 are diagrammatic views respectively of modified circuit details.

In the operation of transmission lines, the power conductors are frequently subjected to heavy potentials due to the release of a bound charge following a stroke of lightning 5 in the vicinity of the line. In many cases it has been customary to install ground or earth wires in order to keep down the resulting potential following the release of a bound charge. The principal function of the ground wire is to increase the electrostatic capacity of the line to earth, as the resulting potential depends upon the charge released and the effective capacity to earth.

Where "Q" represents the charge and "C" the effective electrostatic capacity to ground, the resulting potential "E" will be

$\frac{Q}{C}$

While the presence of the ground wire tends

to reduce the initial charge slightly, its chief function is that of an absorbing electrostatic capacity which tends to prevent a rise in potential. While there is little question but that the ground wire is effective in reducing the maximum potential produced by the release of a bound charge, there are transmission lines where its use does not give the result expected.

In the ordinary functioning of the ground wire, it is evident that if the charge "Q" is not appreciably reduced, owing to the presence of the ground wire, that the electrostatic charge on the conductor will be practically the same, although the potential will be less.

Tests and theory go to show that the losses such as brush discharge increase very rapidly at the higher potentials so that an increase of 40 or 50 per cent in the potential may produce losses many times that at the lower potential.

From this it follows that where a ground wire reduces the maximum potential 30 or 40 percent, the energy losses tending to dissipate the charge will be greatly reduced. Since the total charge is practically the same where the ground wire is present as where it is omitted, it naturally follows that the total effective energy available for setting up or maintaining an abnormal potential on the conductor may be much greater where the ground wire is used than where it is not present since the ground wire tends to delay the dissipation of the charge.

This is particularly true where the induced potentials are high and the rise in potential is exceedingly rapid. Owing to the time lag in flash-over, the potential may rise very rapidly, and owing to the dissipation of energy drop to normal potential so quickly that the insulator may not flash over. If, however, a ground wire is used under the same conditions, the dissipation of energy will be less as explained above; hence, the potential, although of lower magnitude, will be sustained for a longer period of time so that in many cases an arc may take place over the insulator or from conductor to supporting structure, even though the maximum potential has

85

90

95

100

If the ground wire tends to lower the potential so that the surge energy will not be dissipated, allowing the same to be stored a greater length of time, it is possible that 5 more flashovers may take place where a ground wire is used than with the higher potential having an exceedingly rapid rate of decay where the ground wire is omitted.

10 The induced surge on the line with the ground wire may have a considerably longer tail to the wave and, as the total energy is less, the magnitude of the surge at a distance may be higher than where no ground wire is used. This is particularly true where the conductors are such that the losses will be very high 15 at the high potentials. Owing to the effective increase in electrostatic capacity due to the use of a ground wire, the natural period of the system is reduced in accordance with the 20 well known laws. Since the induced losses will be less as the natural period is decreased, it naturally follows that oscillations set up where the ground wire is in place are likely to 25 have a slower period and dampen out less rapidly. A disturbance or wave traveling along the power conductor will induce currents in the ground wire. Where the resistance of the ground wire is low, the I^2R losses due to the induced current will be very small.

30 The energy supplying the losses in the ground wire must be supplied from the power conductor. It is evident that the greater the losses in the ground wire, the greater will be the amount of energy drawn from the power 35 conductor; hence, where the I^2R losses in the ground wire are high due to currents induced by a surge in the power conductor, the dissipation of the surge potential or charge will be rapid and decidedly beneficial. In order 40 to keep the induced potential at the point of disturbance low, it is necessary that the ground wire have an induced potential approximating ground potential. If the resistance or impedance of the ground wire is too 45 high, its efficiency will be lowered. On the other hand, if its resistance is low, its surge dissipating capacity will be reduced. This matter is covered to some extent in my prior Patent No. 1,581,154.

50 In many instances, it is necessary or desirable to use a low resistance ground, either to give life, mechanical reliability, or to keep the maximum induced voltage as low as possible. The low resistance in the ground wire, 55 however, largely eliminates its surge dissipating function. In consequence, I have devised a new method of installing a ground wire so that it will be effective, not only in reducing the maximum surge potential, but at the same 60 time, will possess the surge dissipating capacity of the ground wire. In general, the scheme consists in insulating the ground wire at most of the structures, grounding the same only periodically or through a resistance. By 65 using appropriate resistances, the ground

wire which is insulated from the structure through an insulator can be connected to ground at each structure.

The most suitable absorbing resistance will 70 depend upon the effective electrostatic capacity and the wave front or magnitude of the surge traveling upon the power conductor. This resistance may be varied in different parts of the system, depending upon the results desired. Where the ground wire is connected by a resistance to ground, its absorbing 75 capacity in the vicinity of the disturbance will be greatly reduced as the IR drop over the resistance due to the sudden release of the bound charge will raise the potential of the ground wire similar to that on the power conductor. In order, therefore, that the maximum voltage on the power conductor be reduced, it is essential that the ground wire assume an approximate ground potential as 80 quickly as possible. This is accomplished by establishing a spark gap between the ground wire and earth. This spark gap may be in multiple with the resistance where the resistance is used in the same location. To give 85 most beneficial results, the spark gaps should be used at every support, but the resistances need be used only occasionally. It is evident, however, that where the ground resistance is a few ohms only, the IR drop will be 90 very appreciable. The absorbing resistances may be varied in accordance with the length of span so as to obtain the maximum I^2R loss for currents induced by a surge in the 95 ground wire.

100 As comparatively little is known about the surges on the transmission line, it may be necessary to try several different resistances to obtain the best results. As a matter of fact, a variety of conditions can be taken care of by changing the resistances. Suppose that the resistance at one support is less than 10 ohms. The next support might have a resistance of several hundred ohms and the next one might have a resistance of several thousand ohms. Widely graded resistances of this type could then be used to produce an appreciable loss over a wide range of conditions. Since any I^2R loss will be beneficial and 105 since the shunting gap need have a comparatively low break-down voltage, the efficiency of the ground wire for keeping down the maximum voltage will be effective and, at the same time, the energy of the traveling wave will be dissipated by the resistances. Where the ground wire has an appreciable resistance, it may be grounded only periodically and insulated at the intervening supports. These intervening supports, however, could 110 be equipped with the discharge gaps.

115 Since it is desirable to dissipate as much energy as possible so as to lower the voltage in the surge or traveling wave, it is necessary that the current induced in the ground wire flow over an absorbing or dissipating resist- 120

ance. Where the ground wire is continuous and of low resistance, part of the current will tend to flow along the conductor as well as over the shunt resistance to ground. The 5 higher the shunt resistance, the more current will flow along the conductor, hence, the dissipation of energy may be greatly reduced as against the condition where this current is forced over a high resistance.

10 In many cases, particularly where the resistance of the ground wire is low, it is advisable to split the ground wire up into sections by means of any suitable strain insulator. This sectionalizing insulator may be 15 placed in the middle of the span or at any suitable point. It is advisable, however, that each section of ground wire be connected to earth through an absorbing resistance. If it is desired to provide electrical continuity 20 along the ground wire, the sectionalizing insulator may be shunted by a resistance.

It is evident that where the sectionalizing of the ground wire is frequent that little attention need be paid to the wave length to 25 obtain maximum dissipation of energy, for the difference in voltage between different portions of the power conductor adjacent any section of ground wire will be rather small.

Where a high frequency or oscillation exists on the power conductors so that different portions of the power conductor adjacent a given section of ground wire have potentials, both above and below earth potential, it is 30 evident that there will be a flow of current 35 along the ground wire in the section. If, however, the section of the ground wire is small or equivalent only to an alternation, an appreciable dissipation of energy will be induced in the adjacent section of ground 40 wire and in the ground resistance.

Where a ground wire is installed on wood pole structures embodying the above principles, it is not necessary to use the insulator 45 at intervening points as the wood will furnish sufficient insulation. Gaps, however, which will provide low resistance paths to ground 50 when bridged may be used at each structure or only occasionally where the spans are rather short.

6 It is evident that where the ground wire has an appreciable voltage induced at low or normal frequency, an appreciable energy loss will result in forcing this charging current over the resistance connected to ground, particularly if the resistance is high. Several methods may be used to reduce this loss to any desirable value. In some cases, the location of the ground wire may be such that it will have little resulting potential induced by the voltage in the several conductors. This is shown in my prior Patent No. 1,581,154.

Another method of reducing the loss is to provide a very small gap in series with the resistance to ground, as shown at 30 in Fig. 6. This gap will be such that the voltage

induced at normal frequency will not bridge it but abnormal voltages will cause a breakdown of this gap and allow the resistance to function.

Still another method is to place a reactance, 70 shown at 31 in Fig. 7, in multiple with the resistance. The current induced by the normal frequency in the power conductors would then flow through this reactance. A high frequency, however, would be largely blocked 75 by the reactance and forced over the absorbing resistance. Since the resistance of the reactance coil could be relatively low, the I^2R loss due to current induced at normal frequency would be relatively small.

80 The method applies to practically any type of transmission line and the ground wire may be supported by a suspension or other form of tension insulator, by a rigid insulator or on wood or other members which will supply 85 the necessary resistance so that induced currents will be forced to flow either a considerable distance along the ground wire before 90 going to ground or through the absorbing resistances.

95 In order that the ground wire may have high electrostatic absorbing capacity and assume a ground potential quickly, it is necessary to provide a discharge path which will shunt the insulator or supporting resistance. While it will be possible to support the ground wire with a resistance and shunt gap, in general it is difficult to obtain a resistance of the necessary mechanical properties and which will have a resistance high enough to 100 produce an appreciable I^2R absorption.

105 Fig. 1 shows one form in which the insulator 10 mounted on a support 11 insulates a ground wire 12. The ground wire is held to the insulator by a clamp 13 which forms part of a discharge gap 14. The other part of the gap 15 is connected to ground and may be made adjustable by means of the clamping bolt 16. An absorbing resistance 17 may be attached to the conductor 12. This absorbing resistance may be in any suitable form such as a resistance wire or a liquid placed in a tube. Where a liquid is used, this may be sealed to prevent evaporation or if allowed to evaporate should have a surplus.

115 If a non-freezing liquid is used and provision is made for expansion, the whole may be sealed tightly so that it will require little or no attention in operation. By making the resistance large enough, the energy dissipated in the same will not raise the temperature seriously. Owing to the large number of these which would occur on the transmission line, the load would be relatively small.

120 Unless the ground wire is placed in a neutral field, the normal line potential will induce currents in the ground wire causing a dissipation of energy. This is a disadvantage, but as the current induced is low, compared to that due to the disturbance on the line, it is 130

a comparatively easy matter to reduce these losses materially by periodically connecting the conductor to a low resistance ground and depending upon the resistances at the intermediate points to absorb the abnormal potential.

The ground wire has a comparison in automotive practice. When a car is equipped with a very limber or flexible spring, the 10 bounce is much greater, although the initial shock upon striking a bump is reduced. A ground wire has the same effect upon a power conductor. In automotive practice, it has become customary to install shock absorbers 15 where limber springs are used. In the improved method of installing the ground wire, the absorbing resistances are the equivalent of the shock absorber. The absorbing resistance dampens out the disturbance rapidly 20 similarly to the shock absorber through a dissipation of energy.

Fig. 3 shows diagrammatically a transmission line equipped with a ground wire according to the present invention. The numeral 18 designates supporting structures having electrical transmission lines 19 carried thereon by cross arms 20 and insulators 21. The ground wire 12 is mounted on insulators 10 and is provided at each structure with a 25 spark gap to ground. At greater intervals along the transmission line, the ground wire is connected to earth through resistance elements 17. Sectionalizing insulators 32 may be interposed in the ground wire between the 30 ground connections 17, as previously explained.

In Fig. 4 there is shown a wood pole 22 which may be equipped with the usual form of cross arm, not shown, for supporting the 40 power conductors. An insulator 23 is mounted on the pole 22 and carries the ground wire 12. An arcing member 24 is supported on the ground wire 12 at a distance from the pole 22 and is insulated from the ground wire by 45 means of an insulator 25. A complementary arcing member 26 is electrically connected with the ground wire.

Insulating the conductor 12 from ground 50 may have material advantages in some cases as this arrangement permits the use of the conductor for electrostatic coupling, for carrier current work, or will permit the use of the conductor for signal, pilot wire or other purposes without interfering with its use as 55 a ground wire for reducing the magnitude of surges and for their absorption.

Where a conductor is used for electrostatic coupling, a section of proper length is provided by inserting the sectionalizing 60 insulators 32 shown in Fig. 3. The large discharge gap 14-15 will be set so that discharge will not take place except under an abnormal charge. If an absorbing resistance 17 is used in this section of the line, it will 65 be provided with a discharge gap 30 set large

enough so that the discharge will not take place under the voltage induced on the section by the power line at normal frequency or under the voltage induced on the section by the communication system.

Where the entire conductor 12 is used for signal purposes the gaps 30, while smaller than the gaps 14-15, will be set large enough so that discharge will not take place across these gaps under voltage induced in the conductor 12 by normal line voltage or by normal operation of a signal circuit.

Where it is desired to bleed the line occasionally to keep down high voltages induced at normal frequency, it is advisable to use some means in addition to the resistance 17 and the gap 30 to ground since, if the ground lead is open at the gap 30 no current will flow to ground at normal frequency and voltage and if the gap is closed, flow of current through the resistance 17 would absorb the energy of the signal circuit or dissipate energy taken from the power conductor. If the induced voltage is limited by the discharge of a gap, disturbances will be set up, interfering with communication and radio reception. A suitable reactance 31, however, placed in multiple with the resistance 17 and gap 30 will allow charging current to flow and keep the induced voltage down while preventing a serious loss of energy in the communication system.

Where the voltage induced in the conductor 12 by the normal voltage of the power conductors is considerable, transposition of 100 the power conductors will reduce the resultant voltage on the ground and signal wire 12. In order for this transposition of the power conductors to be effective, however, adjacent sectionalizing insulators must include between them, a sufficient number of transpositions to produce a balanced effect on the conductor 12 or else the sectionalizing insulators must be jumped by reactance 34 which will permit sufficient current to flow 110 at normal frequency to keep the resultant potential down to the desired point.

Where it is desired to sectionalize the conductor 12 occasionally in order to force current induced by a surge over the resistance so as to dissipate the energy, it is evident that the conductor cannot be used for signal purposes. In order to eliminate this difficulty, the sectionalizing insulator 32 may be shunted by a resistance 33. These shunt resistances may be used for absorbing purposes, even though the conductor is not used for communication or other purposes. In some cases the absorbing resistance 33 may be used to take the place of absorbing resistance 17.

I claim:

1. The combination with an electrical transmission line, of a ground wire extending adjacent said line and insulated therefrom to

increase the capacity of said transmission line to ground, said ground wire being connected to earth only through appreciable resistance for dissipating energy induced in said ground 5 wire by abnormal surges in said conductor, and a spark gap between said ground wire and earth for limiting the potential of said ground wire above earth potential to maintain the capacity to earth of said transmission 10 line.

2. The combination with an electrical transmission line, of a support for said line, said line being insulated from said support, a ground wire mounted on said support and 15 insulated therefrom and extending adjacent said transmission line, a resistance element electrically connected between said ground wire and earth, and a spark gap in shunt with said resistance element between said ground 20 wire and earth for limiting the potential of said ground wire above earth potential.

3. A transmission system, comprising a plurality of supports, an electrical transmission line mounted on said supports and insulated therefrom, a ground wire mounted on said supports and insulated therefrom, a resistance element electrically connected between said ground wire and earth, and spark gaps between said ground wire and earth located 25 at spaced positions along said ground wire and forming discharge paths to earth from said ground wire, of which said resistance element is not a part.

4. A transmission system, comprising a plurality of supporting structures, an electrical transmission line mounted on said structures and insulated therefrom, a ground wire mounted on said structures and insulated from said transmission line and said structures, spark gaps interposed between said ground wire and earth and forming arcing paths from said ground wire to earth at spaced positions along said ground wire, and resistance elements electrically connected in 45 shunt with said arcing gaps between said ground wire and earth said resistance elements being spaced from one another at greater distances than the distance at which said spark gaps are spaced from one another 50 along said ground wire.

5. An electrical transmission system, comprising supporting structures, a transmission line carried by said structures and insulated therefrom, a ground wire carried by said structures and insulated from said structures and from said transmission line, a spark gap interposed between said ground wire and earth at each of said supporting structures, and resistance elements electrically connected 55 between said ground wire and earth, the resistance elements so connected being fewer in number than said supporting structures.

6. The combination with an electrical transmission line, of a support for said line, a ground wire extending adjacent said line

and insulated from ground and from said line, and resistance elements of different resistances electrically connected conductively between said ground wire and earth at different points along said ground wire, and arcing gaps forming discharge paths from said ground wire to earth separately and apart from the paths including said resistance elements. 70

7. The combination with an electrical transmission line, of spaced supports for said line, a ground wire carried by said supports and insulated from said transmission line and ground, limiting spark gaps between said ground wire and earth at each of said supports, and resistance elements of varying resistances electrically connected between said ground wire and earth at different positions along said ground wire different from the positions at which said spark gaps are 85 located. 80

8. The combination with an electrical transmission line, of a ground wire extending adjacent said line and insulated from said line and earth, and an adjustable spark gap interposed between said ground wire and earth. 90

9. The combination with an electrical transmission line, of a ground wire extending adjacent said line and insulated therefrom, sectionalizing insulators interposed in said ground wire and dividing said ground wire into sections insulated from one another, each section of said ground wire being electrically connected to earth only through appreciable resistance, and a discharge gap interposed between each section of said ground wire and earth for limiting the potential of said ground wire above earth 95 potential. 100

10. A transmission system, comprising a plurality of supports, and electrical transmission line mounted on said supports and insulated therefrom, a ground wire mounted on said supports and insulated therefrom, sectionalizing insulators interposed in said ground wire and dividing said ground wire into sections insulated from one another, a resistance element electrically connected between each of said ground wire sections and earth, the resistance of said resistance elements being different for different sections of said ground wire, and spark gaps connected between said ground wire and earth and located at spaced positions along said ground wire. 110 115

11. The combination with an electrical transmission line, of a support for said line, said line being insulated from said support, a ground wire mounted on said support and insulated therefrom and extending adjacent said transmission line, a conductor path having a resistance element therein electrically connected between said ground wire and earth, a spark gap connected between said 120 125 130 135

ground wire and earth, for limiting the potential of said ground wire above earth potential, and means in said conductor path for producing a greater dissipation of energy therein for high frequency potentials imposed on said path than for low frequency potentials.

12. The combination with a transmission line, of a support on which said line is mounted and from which it is insulated, a supplemental conductor mounted on said support and insulated from said support and said transmission line, sectionalizing insulators interposed in said conductor, and resistance elements shunting said sectionalizing insulators.

13. The combination with a transmission line, of supports for said line on which said line is mounted and from which it is insulated, a supplemental conductor mounted on said supports and insulated therefrom and extending adjacent said transmission line, sectionalizing insulators interposed in said supplemental conductor, resistance elements shunting said insulators, ground leads connected with each section of said supplemental conductor and having resistance therein, and arcing gaps interposed between each section of said supplemental conductor and ground.

14. The combination with a transmission line, of supports for said line, a supplemental conductor extending adjacent said line, said line and supplemental conductor being insulated from each other and from said supports, sectionalizing insulators for said supplemental conductor dividing said supplemental conductor into sections, impedance jumpers for said sectionalizing insulators, and a ground connection for said supplemental conductor having a discharge gap and resistance in series therein.

In testimony whereof I have signed my name to this specification this 20th day of August A. D. 1928.

ARTHUR O. AUSTIN.
